ATTORNEY

UNITED STATES PATENT OFFICE

RUSSELL R. WATERMAN, OF LONG BEACH, CALIFORNIA, ASSIGNOR TO FARMERS' NATIONAL BANK OF GREENVILLE, OHIO, TRUSTEE, OF GREENVILLE, OHIO, A CORPORATION OF OHIO

WATER SEAL FOR STEAM POWER PLANTS

Application filed April 22, 1926. Serial No. 103,809.

My invention relates to water seals for power plants, more particularly an apparatus for separating the air from the water being sent to the boiler pumps in power plants, and the objects of my invention are: first, to provide a means for separating the air from the water in its passage from the condenser to the boiler and returning the same to the condenser; second, to provide an apparatus of this class which is positive in its action; third, to provide a novelly constructed water seal of this class and, fourth, to provide an apparatus of this class which is simple and economical of construction, positive in its action, efficient, durable and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a diagrammatic sectional view through 1—1 of Figure 2 of my apparatus showing some of the parts and portions in elevation to facilitate the illustration. Figure 2 is a sectional view through 2—2 of Figure 1 and Figure 3 is a fragmentary sectional view through 3—3 of Figure 1.

Similar characters of reference refer to similar parts and portions throughout the several views of the drawings.

The separating chamber 1, separating chamber cover 2, diaphragm 3, water valve stem 4, washer 5, nut 6, outlet conductor 7, adjusting screw 8, conductor to condenser 9, water valve stem spring 10, drain valve 11, water valve 12, water outlet conductor to the boiler pump 13, conductor 14, bypass piston valve 15, branch conductor 16, bypass valve intake passage 17, condenser pump intake 18, gear pump 19, gear pump drive shaft 20, and stuffing box 21 constitute the principal parts and portions of my water seal apparatus.

The separating chamber housing 1 is a hollow, cylindrical member provided with a flange 1a at its upper end, over which is mounted a cover member 2, which is also provided with a flange 2a conforming to the flange 1a; and interposed between the flanges 1a and 2a, extending across the upper end of the member 1, is a diaphragm 3. Secured to this diaphragm 3 is the upper end of the valve stem 4, which valve stem 4 is provided on its upper end above said diaphragm with a flanged washer which is held in position by means of a nut 6 secured on the upper end of the stem 4. Upon this washer 5 is mounted a compression spring 10 which is positioned in an inverted cup shaped portion 2b mounted centrally on the cover member 2. Thus it will be noted that there is provided both the spring 10 and the diaphragm 3 for regulating the movement of the valve stem 4. Secured on the lower end of the valve stem 4 is a valve 12 which seats in an orifice 1b in the lower central portion of the housing 1. This housing 1 is provided below the orifice 1b with a side outlet 13, which connects the valve 12 with the boiler pump. This casing 1 is also provided with a valve 11 which serves as a drain valve. This housing 1 is also provided near its upper end with an outlet conductor portion 7 which is provided in one side with a set screw 8 which serves as an adjusting screw for adjusting the opening in the outlet 7. Mounted in the extended end of this outlet portion 7 is a conductor 9 which extends to and connects with the condenser not shown. Communicating with the separating chamber 1 near its lower side is a conductor 14 and its opposite end communicates with one side of a gear pump 19 which is of the conventional type, and the other side communicates with the conductor 18 which leads to the condenser. This conductor 18 is provided with a branch 16 which communicates with a small orifice 15a in the piston 15 which is reciprocally mounted in an upright housing 15b in which the piston is mounted, and this piston is provided with a spring 15c tending to hold it downwardly against the shoulder 15d in the housing 15b. The interior of this housing is provided with

a bypass 17 communicating with the conductor 14. The pump 19 is provided with an extended shaft 20 provided with a housing upon which is mounted a stuffing box 21 5 for providing a seal around said shaft.

The operation of the water seal apparatus is as follows: Water is pumped from the condensers through conductor 18 by means of the gear pump 19 and passes through the conductor 14 into the chamber 1 in which the air is in the upper portion of the chamber and the water in the lower portion. When the water reaches a certain level, pressure is brought to bear on the diaphragm 3 by the air and water in said chamber 1 which actuates the diaphragm 3 compressing the spring 10 and opening the valve 12 permitting the water to be pumped by the boiler pump through the outlet 13. The air in the upper portion of the chamber 1 passes outwardly through the conductor 7, conductor 9 to the condenser above the pump intake. When there is no air in the chamber 1 the conductor 7 merely bypasses a small portion 20 of the water pumped and has no effect on the operation of the rest of the apparatus. The flow of air and also the pressure caused by the water and air in the chamber 1 is regulated by the adjusting screw 8 which is 25 adapted to adjust the size of the outlet in the portion 7. When the pressure lowers in the chamber 1 the valve 12 will close on the seat 16. The water will then pass directly from the condenser into the pump 19 into the 30 housing 1 raising the pressure again. When the pressure is high in the chamber 1 and all the water is not being pumped from the chamber 1, the water will be pumped from the condenser through the pump 19 into the conductor 14 to the by-pass 17 and the 35 back pressure will raise the piston 15 permitting the water and air to pass outwardly through the branch 16 and back through the conductor 18 to the condenser pump intake and through the pump again.

Though I have shown and described a particular construction, combination and arrangement of parts and portions, I do not wish to be limited to this particular construction, combination and arrangement but desire to include in the scope of my invention the construction, combination and arrangement substantially as set forth in the appended claims.

Having thus described my invention, what I claim as new and desire to secure by Letters Patent is:

1. In a water seal apparatus for power plants, a vertical chamber member having a discharge opening at its lower end, a diaphragm extending over the upper end of the chamber member, a spring positioned above the diaphragm exerting force downwardly thereagainst, a valve stem extending downwardly from the diaphragm and having a

valve at its lower end adapted to seat over the discharge opening, an inlet opening extending through the side of the chamber member near the lower end thereof, and a discharge conductor connected to the upper end of the chamber member below the diaphragm and above the inlet opening and of smaller diameter than the inlet opening. 70

2. In a water seal apparatus for power plants, a chamber provided with a diaphragm in its upper end, a valve supported by said diaphragm and seated in the lower end of the chamber, a boiler feed outlet conductor communicating with the lower end of said chamber and controlled by said valve, a second outlet conductor connected with the upper portion of said chamber below said diaphragm, and an inlet conductor connected near the lower portion of said chamber. 75

3. In an apparatus of the class described, a separating chamber connected to a water source, a pressure actuated valve connected with and actuated by the pressure within the chamber, a water outlet conductor communicating with said valve, and a second outlet conductor connected with the upper portion of said chamber and communicating with and adapted to discharge into said water source. 80

4. In an apparatus of the class described, a separating chamber connected to a water source, a pressure actuated valve in said chamber, a water outlet conductor communicating with said valve, and a second outlet conductor connected with the upper portion of said chamber and communicating with and adapted to discharge into said water source. 85

5. In an apparatus of the class described, a separating chamber connected to a water source, a pressure actuated valve in said chamber, a water outlet conductor connected with the lower portion of said chamber, the pressure actuated valve controlling the supply of water from said chamber to said outlet conductor, and a second outlet conductor connected with the upper portion of said chamber and adapted to permit free discharge therefrom to said water source. 90

6. In an apparatus of the class described, a separating chamber connected to a water source, a pressure actuated valve connected with and actuated by the pressure within the chamber, a water outlet conductor connected with the lower portion of said chamber, the flow of fluid from said conductor being controlled by said valve, and a second outlet conductor connected with the upper portion of said chamber and adapted to permit free discharge therefrom to said water source. 95

In testimony whereof, I have hereunto set my hand at Los Angeles, California, this 15th day of April, 1926.

RUSSELL R. WATERMAN.
